US0D1025373S

(12) **United States Design Patent** (10) **Patent No.:** **US D1,025,373 S**
Li (45) **Date of Patent:** **** Apr. 30, 2024**

(54) **PHYSIOTHERAPY DEVICE**

(71) Applicant: **Shenzhen Yuchua Linrui Technology Co., Ltd.**, Guangdong (CN)

(72) Inventor: **Lianghao Li**, Guangdong (CN)

(**) Term: **15 Years**

(21) Appl. No.: **29/800,133**

(22) Filed: **Jul. 19, 2021**

(51) LOC (14) Cl. **24-01**

(52) U.S. Cl.

USPC **D24/200**; D24/215

(57) **CLAIM**

The ornamental design for a physiotherapy device, as shown and described.

DESCRIPTION

FIG. 1 is a bottom, front, right perspective view of a physiotherapy device, showing my new design;

FIG. 2 is a front elevation view thereof;

FIG. 3 is a rear elevation view thereof;

FIG. 4 is a left elevation view thereof;

FIG. 5 is a right side elevation view thereof;

FIG. 6 is a top plan view thereof;

FIG. 7 is a bottom plan view thereof; and,

FIG. 8 is a front, left, top perspective view thereof.

In the drawings, the equal-length broken lines depict portions of the physiotherapy device that form no part of the claimed design.

1 Claim, 8 Drawing Sheets
